UNITED STATES PATENT OFFICE.

GEORGE L. PIERCE AND HENRY V. RAU, OF BROOKLYN, NEW YORK, ASSIGNEES TO
A. G. SPALDING & BROS., OF NEW YORK, N. Y., A CORPORATION OF NEW JERSEY.

GOLF-BAG BOTTOM.

Application filed January 22, 1926. Serial No. 82,893.

This invention relates to golf bags, and has for its object the provision of a bottom structure that is durable and rigid and at the same time presents a neat and attractive 5 appearance.

The bottom of a golf bag is subjected to such severe treatment that it should be constructed of metal, especially the rim which contacts with the ground. But in working 10 for strength and long wear the important factors of light weight and pleasing appearance must not be overlooked, and the problem of attaching the metal parts to the leather or canvas bag in an inconspicuous 15 and lasting manner must be solved.

In the present invention, the bottom itself is a piece of leather, two metal rings being used to clamp the bottom to the bag. The metal rings are secured together by a rolled 20 seam that reinforces the bottom and acts as a combined shock absorber and wear plate. The bottom structure is thereby reinforced with metal at the points of greatest stress and wear, but the amount of metal used is 25 kept at a minimum, thereby keeping down the weight and avoiding the heavy metallic appearance resulting from a too-liberal use of metal.

This invention provides a bottom in which 30 a downwardly projecting rim of the bag is bound between two metal rings. One of these rings has a flange gripping a projecting portion of the bag, the other ring having a portion engaging and supporting the 35 leather bottom of the bag.

Other features and advantages of the invention will become apparent during the course of the description, in which a preferred embodiment is set forth by way of 40 example.

In the drawings:—

Fig. 1 is an elevation of the lower end of a golf bag, parts being broken away to show the construction.

Fig. 2 is a fragmentary sectional view of a modification.

Fig. 3 is a bottom view of a bag incorporating the structure shown in Fig. 2.

Referring more specifically to the drawings, the tubular body of the bag shown at 50 1 may be made of canvas, leather or other suitable material. A leather reinforcing band 2 is secured about the lower end of

the body, and an attaching strip 3 is fastened to the lower end of band 2. 55

The leather bottom piece 4 has a depending flange 5 which if desired can be stitched to the bag body. A disc 6 of fibre or similar stiff material, and a felt pad 7, are placed above the leather bottom. 60

The bottom ring, made of aluminum, has a cylindrical flange 8 and a lateral flange 9. The flange 8 terminates in a rolled bead 10 upon which the leather bottom piece 4 rests. The bead 10 may be made stiffer by rolling 65 it about a wire ring if desired.

The attaching ring 11, also of aluminum, fits closely about the strip 3 and has an inwardly extending flange 12 which engages with the upper side of strip 3. The lower 70 part of ring 11 carries an outstanding flange 13 which is rolled with the flange 9 to form a double rolled bead as clearly shown in the drawing. A ring 14 is placed at the angle of the bottom ring to stiffen and reinforce the 75 structure.

In the modification shown in Figs. 2 and 3 the same general arrangement is used. But in this case the upper end of flange 8 is bent inwardly to form a supporting flange 15. 80 The flange 15 may be formed with extensions 16 to further support the leather bottom. These extensions 16 may be as large as desired and may have the leather bottom secured thereto by rivets or other suitable fastening means. 85

In both of the species disclosed, the flange 8 carries an inwardly extending portion that contacts with and supports the bottom piece 4. The inwardly extending portion bends 90 away from the flange 8 in such manner as to conform to the curve between the bottom piece 4 and the flange 5, thereby avoiding any cutting or excessive wear on the leather.

In a golf bag constructed according to 95 this invention a limited amount of metal is used to bind the parts of the bag together and to reinforce and strengthen the bag at the points of greatest wear. At the same time the bottom itself is composed of leather, 100 which combines with the aluminum or nickel metal parts to present a sturdy and at the same time a pleasing appearance.

What we claim is:

1. In a golf bag, a body, a bottom piece, 105 an attaching ring secured to said body, and

2
a bottom ring having an inwardly extending supporting portion engaging said bottom piece, said bottom ring being attached to the bag solely by being rolled with the attaching ring to form a bead.

5. 2. In a golf bag, a body, a bottom piece, a strip secured about said body, an attaching ring having a flange engaging said strip, and a bottom ring secured to the bag solely by being rolled with said attaching ring to form a bead, said bottom ring having a cylindrical flange, the upper end of which is bent to form a support for said bottom piece.

10. 3. In a golf bag, a body, a band independently secured to the body, a metallic attaching ring surrounding the band and carrying an outstanding bead, a metallic bottom ring fitting within the body and having an outstanding flange secured to the

bead, the bottom ring being held on the body by a flange formed on the attaching ring and extending over the end of the band, and a leather bottom piece having a cylindrical part extending between the bottom ring and the bag body.

15. 4. In a golf bag, a body, a bottom piece within the body and having a flange extending along the wall of the body, an attaching ring secured about said body, a bottom ring secured to the attaching ring to form a bead, one end of the bottom ring projecting past the lower end of the flange on the bottom piece, said end of the bottom ring being bent to form a support for said bottom piece.

20. In testimony whereof we affix our signatures.

GEORGE L. PIERCE.
HENRY V. RAU.
